[57] **ABSTRACT**

Crude argillaceous potassium salts are separated by first subjecting the crude salt to a conditioning with 2,6-dinitrophenol or a mixture of said dinitrophenol, a halogenocarboxylic acid and water and thereafter the thus-conditioned salt is passed through an electrostatic separator in which a warm atmosphere is maintained, thereby producing a separation of the particles of the salt into two fractions, one containing clay and rock salt at the positive electrode and the other containing sylvite and kieserite at the negative electrode of the electrostatic separator.

9 Claims, No Drawings

**PROCESS FOR THE ELECTROSTATIC
SEPARATION OF CLAY CONTAINING CRUDE
POTASSIUM SALTS**

halogenocarboxylic acid and water and thereafter the thus-conditioned salt is passed through an electrostatic separator in which a warm atmosphere is maintained, thereby producing a separation of the particles of the salt into two fractions, one containing clay and rock salt at the positive electrode and the other containing sylvite and kieserite at the negative electrode of the electrostatic separator.

BACKGROUND OF THE INVENTION

In German Pat. No. 2,007,677 an electrostatic separation process is described for argillaceous crude potassium salts wherein the salt is treated with lactic acid in combination with a halogeno-carboxylic acid and wherein the thus conditioned mass after heating to a temperature between 20° and 65° C is then separated in an electrostatic separation. At the positive electrode clay separates out while the virtually clay-free crude salt is deposited at the negative electrode. The crude salt from which the clay thus has been removed can then be further processed to obtain high percentage sylvite concentrates.

SUMMARY OF THE INVENTION

It has now been found that when the conditioning is effected with dinitrophenol, specifically 2, 6-dinitrophenol, or a mixture of such dinitrophenol, a halogeno-carboxylic acid and water a reversal of the polarity of the charge is effected in the salt. As a result the argillaceous minerals will be charged negatively together with the rock salt and both can therefore be obtained directly as residual fraction. Such reversal does not occur with the sylvite and kieserite. These two materials are therefore deposited together at the positive electrode. There is thus obtained a sylvite-kieserite fraction which can either be used directly as a valuable K-Mg-fertilizer or can be further processed to obtain a high percentage sylvite or kieserite concentrate. There is thus obtained a selective charging of the argillaceous materials and of the rock salt on one hand and of the sylvite and kieserite on the other hand.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

**DETAILS OF THE INVENTION AND SPECIFIC
EMBODIMENTS**

Preferably the conditioning is effected by vigorous mixing of the conditioning agent or agents with the crude potassium salt. Preferably the relative humidity

to which the salt is exposed is between 2 and 20 and most preferably between 5 and 15 percent. The salt is heated prior to the charge. The amount of 2,6-dinitrophenol should be between 50 and 500 g/t, preferably between 75 and 200 g/t. The halogeno-carboxylic acid preferably is chloroacetic acid which may be used in amounts of 50 to 500 g/t, preferably of 75 to 300 g/t. The water should be present in amounts between 1 and 4,000 g/t preferably in an amount between 500 and 3,000 g/t.

The time of conditioning by intensive mixing may be between 10 and 120 sec. and preferably is between 20 and 60 sec. The separation is preferably effected at a temperature between about 25° and 65° C.

The following examples will further illustrate the invention.

The starting product in these examples was a sylvinite having the following chemical and screen analysis:

Chemical Analysis

KCl	=	18.61 %
K ₂ SO ₄	=	0.78 %
MgCl ₂	=	0.04 %
MgSO ₄	=	21.27 %
CaSO ₄	=	0.63 %
NaCl	=	52.72 %
H ₂ O	=	3.32 %
HCl		
insolubles	=	2.47 %

Mineral Analysis

Sylvite	=	18.7 %
Langbeinite	=	1.5 %
Polyhalite	=	0.6 %
Kieserite	=	22.0 %
Anhydrite	=	0.7 %
Rock salt	=	52.0 %
Clay mineral	=	4.5 %

Screen Analysis

0.8 -	0.8	mm =	2.7 %
0.5 -	0.5	mm =	47.6 %
0.25 -	0.25	mm =	29.5 %
0.25 -	0.16	mm =	8.0 %
0.16 -	0.1	mm =	5.2 %
	0.1	mm =	7.0 %

In the Tables below the following symbols have been used:

+= fraction at the positive electrode.

M = middlings.

- = fraction at the negative electrode.

EXAMPLE 1

The tests incorporated in this Example were carried out at a 10 percent relative humidity corresponding to an absolute air humidity at 39°-47°C of 5-7 g/m³. The separations were effected in a gravity (free fall) separator with a throughput of about 10 t/m · h:

TABLE 1

Test No.	Conditioning Agent	g/t	K ₂ O contents %		NaCl contents %		Clay contents %	
			+	-	+	-	+	-
1	Fatty acid	150	32.2	2.2	45.4	18.1	3.4	0.9
2	orthocresotic acid	150	47.6	2.5	16.0	54.8	4.3	0.7

TABLE 1—Continued

Test No.	Conditioning Agent	g/t	K ₂ O contents %		NaCl contents %		Clay contents %	
			+	-	+	-	+	-
3	orthocresotic acid	100						
	+Lactic acid	100	10.0	13.2	22.4	59.7	15.9	0.4
	+Acetic acid	200						
4	Lactic acid	100						
	+Trichloro Acetic acid		11.7	13.6	19.5	60.0	23.8	0.2
5	2,6-dinitrophenol	200						
		150	4.6	18.8	78.0	27.9	4.1	0.6

The tests Nos. 1 and 2 as well as Nos. 3 and 4 illustrate the prior art. They show that the argillaceous minerals have the same charge as the sylvite (Tests Nos. 1 and 2 or that they have the same charge as the rock salt and kieserite while the opposite charge is placed on the sylvite (Tests Nos. 3 and 4 which illustrate the process of the above-mentioned German patent).

Test No. 5 illustrates the process of the present invention. As appears by using 2,6-dinitrophenol as conditioning agent an equal negative charge is placed on the clay and rock salt as against the sylvite and kieserite. Accordingly there are obtained virtually clay-free sylvite-kieserite fractions at the negative electrode which can then be further processed to obtain sylvite and kieserite concentrates. The NaCl-fraction which is high in clay and comprises 78.0 percent NaCl and 4.1 percent HC1 insoluble material accordingly contains only about 6 to 10 percent of the total initial sylvite. This fraction can then be discharged directly as the residual fraction and can thus be eliminated from the subsequent sylvite processing operation.

EXAMPLE 2

This Example illustrates that chloroacetic acid and water improve the effects obtained by the dinitrophenol. The sylvite then is eliminated to a higher degree in the concentrate and rock salt is eliminated at a higher amount in the residue. The combination of conditioning agents comprising 2,6-dinitrophenol, chloroacetic acid and water constitutes the optimum of the simultaneous separation of rock salt and clay on one hand and sylvite and kieserite on the other hand.

The following Table further illustrates a test with the combination of 2,6-dinitrophenol, H₂O, and trichloroacetic acid. In this test there were used the following amounts: 200 g/t dinitrophenol, 1,500 g/t water and 300 g/t trichloroacetic acid. The separations were carried out at a relative humidity of 5 percent corresponding to 55°C at an absolute humidity of 5.5 g/m³.

TABLE II

	K ₂ O	NaCl	Kieserite	HCl (insoluble)
Contents (%)				
Crude salt	12.2	52.0	22.0	2.5
Concentrate	26.6	19.2	37.1	0.4
Residue	1.4	76.0	12.2	3.9
Fractions (%)				
Crude salt	100	100	100	100
Concentrate	93.5	15.5	66.4	6.3
Residue	6.5	84.5	33.6	93.7

The Table II indicates the fraction ("concentrate") deposited at the negative electrode and the fraction ("residue") eliminated at the positive electrode.

The process of the invention permits to obtain a com-

mon charge between the clay and the rock salt as against the charge on the sylvite and kieserite. From a 15 crude salt containing 12.2 percent K₂O and 2.5 percent HC1 insolubles there were obtained, at a single pass through the separator, a concentrate with 26.6 percent K₂O and only 0.4 percent HC1 insolubles at the negative electrode. The sylvite recovery in the concentrate 20 was 93.5 percent.

The clay fraction in the residue contained 93.7 percent of the clay which had been introduced with the 25 crude salt and was thus eliminated. At the same time 84.5 percent of the rock salt were also eliminated in the residue.

These figures illustrate the substantial advance of the 30 process of the invention. The separation operation can be carried out with throughputs of 5 to 30 t of crude salt per meter of width of electrode and hour. This means that the size of the electrode (width) can be reduced 30 to 180 times as against the prior art. This thus permits huge savings in apparatus investment and cost of operation and also results in a substantial increase of the safety of the operation.

35 The high selectivity regarding the clay of the process of the invention is such that the clay is practically quantitatively eliminated from the salt in a single stage operation. There is thus obtained at the negative electrode a virtually clay-free crude salt which is high in K₂O contents and which can then be further processed in well known manner to obtain a higher K₂O yield and maximum concentrates with at least 60 percent. This crude salt which is free of clay and high K₂O contents has been freed of most of the rock salts. Thus in a subsequent sylvite separation operation only a comparatively low amount of salt will be deposited. This again leads to substantial savings in investments and cost of operation.

40 As has already been indicated the inventors have also 45 found that water substantially increases the effects of the 2,6-dinitrophenol. The amount of water to be used depends on the relative humidity of the atmosphere to which the salt has been exposed prior to the treatment with the conditioning agents and prior to the heating to the separation temperature. Thus at a high relative humidity of the atmosphere less water need be added during the condition while the amount of water is higher at a low relative humidity. The amount of water that must be used varies between 1 and 4,000 g/t, and preferably is between 500 and 3,000 g/t.

EXAMPLE 3

50 The tests of this Example further illustrate the substantial advance of the process of the invention. I. Clay and NaCl separation according to the process of the 55 invention

TABLE III

	K ₂ O contents (%)	NaCl contents (%)	HCl contents (insoluble) (%)	K ₂ O yield (%)	HCl (insolubles) yield (%)
Crude salt	12.2	52.0	2.5	100	100
Concentrate	28.0	21.0	0.5	92.7	9.4
Residue	1.5	81.5	4.3	7.3	90.6

II. Separation of the concentrate by conventional flotation process:

TABLE IV

Test No.	K ₂ O-contents % concentrate	K ₂ O-contents % residue	K ₂ O-yield % relative to initial flotation mass	relative to crude salt
1 without electrostatic pre-treatment	40.0	2.12	86.1	86.1
2 after electrostatic pretreatment according to invention	48.6	1.38	97.8	90.6

The clay and NaCl separation according to the process of the invention was carried out by conditioning of the argillaceous crude salt with 200 g/t 2,6-dinitrophenol, 1,000 g/t water and 300 g/t trichloroacetic acid at a relative humidity of 7.5 percent in heated air.

The subsequent separation by flotation of the virtually clay-free concentrate of high K₂O contents was effected with 25 g/t guar flour, 50 g/t amine, 15 g/t oil and 15 g/t of a water insoluble flotation foamer consisting of intermediate and higher ether-alcohols (sold under the trade-mark "Flotanol" by the Farbwerke Hoechst). This is represented by test No. 2 of Table 4. Test No. 1 of the same table has been added only for comparison purposes to show the direct flotation of a crude salt without electrostatic preceding preparation.

The direct flotation of the argillaceous crude salt resulted in a concentrate of 40.0 percent K₂O which was equivalent to a K₂O yield of 86.1 percent. The flotation after treatment of a substantially clay-free concentrate as obtained by the process of the invention which was high in K₂O contents is shown in test No. 2. In this case there was obtained a flotation concentrate of 48.6 percent K₂O. Relative to the mass employed for the flotation step which was constituted by the concentrate obtained in Test No. 1 the K₂O yield was 97.8 percent. Relative to the crude salt the K₂O yield was 90.6 percent.

The preliminary clay separation by the process of the invention therefore results in better K₂O concentrates and better K₂O yields in the subsequent sylvite recovery process.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected

by Letters Patent is set forth in the appended claims:

1. In a process for the electrostatic separation of particles of a crude argillaceous potassium salt which includes clay, rock salt, sylvite and kieserite in which the particles of the crude salt are first subjected to treatment with a conditioning agent and are then charged electrostatically and passed through an electrostatic separator to separate the components of the crude argillaceous potassium salt into two fractions containing different proportions of its individual components, the improvement which comprises conditioning the particles of the crude salt by intimately mixing them with a
